DOOR HINGE

Charles F. Mink, Port Chester, N. Y.

Application December 18, 1957, Serial No. 48,947

Term of patent 14 years

(Cl. D10—9)

FIG. 1

FIG. 2

FIG. 3

FIG. 4

Fig. 1 is an isometric view of a door hinge showing my new design, the wings of the hinge being illustrated in open position;

Fig. 2 is a top plan view of the hinge shown in Fig. 1;

Fig. 3 is a front elevation view; and

Fig. 4 corresponds to Fig. 2 and illustrates the wings in closed position.

I claim:

The ornamental design for a door hinge, substantially as shown.
